ATTORNEY.

UNITED STATES PATENT OFFICE.

RICHARD C. KEOGAN, OF SOUTH BEND, INDIANA.

CONCRETE-WALL MOLD.

1,400,682.

Specification of Letters Patent. Patented Dec. 20, 1921.

Application filed November 29, 1920. Serial No. 427,131.

To all whom it may concern:

Be it known that I, RICHARD C. KEOGAN, a citizen of the United States, residing at South Bend, in the county of St. Joseph and 5 State of Indiana, have invented certain new and useful Improvements in Concrete-Wall Molds, of which the following is a specification.

The invention relates to concrete wall 10 molds and has for its object to provide a device of this character wherein wall sections having vertical columns at their ends may be formed in such a manner that each section will be interengaged and the window openings in the sections formed around a window frame disposed between detachable mold sections.

A further object is to provide a wall mold 15 formed from a pair of spaced members, one of said members being provided with vertically disposed recesses for forming a column and with a detachably vertically disposed removable member for forming a vertically disposed recess in the column. Also 20 to provide the adjacent faces of the mold sections with inwardly extending bevel flanges adapted to receive therebetween and engage a window frame, thereby allowing a window opening to be formed with the 25 frame therein, said bevel flanges and frame being of sufficient width to maintain the inner walls of the mold sections in spaced parallel relation to each other.

With the above and other objects in view 30 the invention resides in the combination and arrangement of parts as hereinafter set forth, shown in the drawings, described and claimed, it being understood that changes in the precise embodiment of the invention 35 may be made within the scope of what is claimed without departing from the spirit of the invention.

In the drawings:—

Figure 1 is a side elevation of a completed wall section, showing the mold in position for forming an adjacent interengaged wall section.

Fig. 2 is a top plan view of a formed wall section, showing the mold in position 50 for forming an adjacent interengaged wall section.

Fig. 3 is a perspective view of one of the mold sections, showing a portion of the column of a formed wall section.

55 Fig. 4 is a perspective view of the strip

used to make the groove in the side of the column.

Referring to the drawings, the numeral 1 designates a wall section having at one of its ends a vertically disposed integral column 2. The columns 2 have their side faces formed with vertically disposed recesses 3 for the reception of the adjacent ends 4 of the wall sections, thereby interengaging the wall section and preventing displacement of the sections in relation to each other. Each section 1, if so desired is formed with a beveled opening 5, preferably rectangular shaped and in which opening a window frame 6 is disposed. The window frame 6 is preferably placed between the bevel flanges 7 of the mold sections 8 and 9 and with which frame said bevel flanges 7 engage thereby utilizing the frame 6 for forming the window opening, and at the same time allowing the frame to be securely held in the window opening 5 when the wall section is formed.

The mold sections 8 and 9 have their inner walls 10 and 11 spaced from each other by the bevel flanges 7 and the window frame 6 and are held in spaced parallel relation to each other by said bevel flanges and frame 6. The ends of the sections 8 and 9 are provided with vertically disposed recesses 11, which recesses form the columns 2 at the ends of the wall sections 1, the vertical recess 3 being formed by the removable vertically disposed strip 12, the sides of which are engaged by the sides 13 of the column forming flanges and is held therebetween in any suitable manner. Vertically disposed strip 12 is of sufficient width that the sides 13 of the column forming flanges 14 are in engagement with the sides of the strip 12, the inner walls 10 will be in spaced parallel relation to each other. The sides 8 and 9 are built up from boards having longitudinally disposed reinforcing bars 15 which are held in spaced relation with each other by means of vertically disposed bars 16 which are nailed or otherwise secured to the longitudinally disposed bars 15. One of the ends of the bars 15 extend beyond the ends of the column forming portions of the mold sections 8 and 9 and have secured thereto horizontally disposed blocks 17, the blocks 17 of the section 8 abutting the blocks 17 of the section 9 and engaging the outer faces of the flanges 14 in such a manner that

110

they form means for additionally holding the vertically disposed strip 12 against outward displacement when concrete is disposed between the mold sections 8 and 9.

- 5 5. The ends 18 of the mold sections 8 and 9 are provided with vertically disposed angles 19, the flanges 20 of which are spaced from each other substantially a distance equal to the thickness of the column 2 and engage
- 10 10. the outer faces of said column with the ends 18 of the mold sections in engagement with the end face of the column 2, in such a manner that the vertically disposed recess 3 will register with the space between the
- 15 15. mold sections 8 or 9. When concrete is poured between the mold sections 8 or 9 another wall section similar to the wall section 1 is formed with a vertically recessed column at one end and with its
- 20 20. other end interengaged with the vertical recess 3 of the column 2 of the wall section 1 which has been previously formed. The operation is repeated as desired until a wall is formed of the desired length.
- 25 25. 6. The mold is particularly adapted for use in constructing small houses, such for instance as garages and one story houses, however it is to be understood that houses of two or more stories may be also formed
- 30 30. if so desired.

The mold sections 8 and 9 after being placed in position as shown in Fig. 2 may be cleated together across their tops or ends as desired, said cleating varying according

35 to working conditions.

The invention having been set forth what is claimed as new and useful is—

1. A sectional wall forming mold comprising a pair of spaced mold sections, said
- 40 40. mold sections having their inner faces provided with inwardly projecting window opening forming members adapted to engage opposite faces of a window frame, one end of each mold section being provided

with vertically disposed column forming 45 recesses and a substantially centrally disposed vertical removable strip interposed between the ends of the mold sections adjacent the column forming recesses and forming means for forming a vertically disposed recess in the end face of a column. 50

2. A sectional wall forming mold comprising a pair of spaced mold sections, said mold sections having their inner faces provided with inwardly extending beveled 55 window opening forming members adapted to engage opposite faces of a window frame, said window opening forming members and the window frame held therebetween forming means for maintaining the mold sections 60 in spaced parallel relation to each other, one end of each of the mold sections having a vertically disposed column forming recess, a removable strip disposed between the recessed ends of the mold sections and extending 65 inwardly, and members carried by the opposite ends of the mold sections for engaging opposite sides of an adjacent column and forming means for maintaining the chamber of the mold in registration with a 70 vertically disposed recess in said adjacent column.

3. A sectional wall forming mold comprising a pair of spaced mold sections, said sections having inwardly extending members 75 on their adjacent faces for engaging opposite sides of a window frame for forming the wall around said window frame, vertical oppositely disposed recesses at the ends of the mold sections, a vertically disposed strip disposed between the recessed ends of the mold section and extending inwardly, and means for maintaining the mold sections in spaced relation to each other. 80

In testimony whereof, I affix my signature.

RICHARD C. KEOGAN.
